UNITED STATES PATENT OFFICE

PAUL T. EDGAR, OF ARCOLA, ILLINOIS

BOTTLE CLEANING BRUSH

Application filed April 9, 1931. Serial No. 528,892.

This invention relates to improvements in brushes, and the primary object of this invention is to provide a brush especially adapted for cleaning the interior of a milk bottle or like receptacle.

A still further object of the invention is to provide an expansible brush that is normally collapsed, and which in a collapsed condition is inserted in the milk bottle, and may be subsequently expanded for forcing the bristles of the brush into engagement with the inner face of the bottle to facilitate cleaning the same when the brush is rotated.

Other objects and advantages of the invention will become apparent from a study of the following description, taken in connection with the accompanying drawings wherein:

Figure 1 is a side elevational view of the brush embodying the features of the present invention, the same being inserted in a milk bottle and shown in an expanded position for engagement with the inner face of the bottle.

Figure 2 is a side elevational view of the brush per se, the same being in a collapsed or retracted position.

Figure 3 is a transverse sectional view taken substantially on the line 3—3 of Figure 1.

Figure 4 is a similar view taken substantially on the line 4—4 of Figure 2.

Figure 5 is a bottom plan view of the brush.

Figure 6 is a perspective view of a U-shaped clamping element forming a part of the present invention.

With reference more in detail to the drawings, it will be seen that 5 designates a substantially inverted U-shaped rectangular frame preferably formed of two strands of wire twisted one about the other and providing for the frame a crown or connecting portion 6, parallel side portions 7, with the latter portions 7 at their free ends provided with bent portions 8 disposed inwardly of the frame and laterally of each other as shown in Figures 1 to 3 inclusive, and preferably with the bent portions 8 terminating in upwardly extending terminals. Thus the members 7 provide substantially the L-shaped legs

for the frame and are connected at their upper ends by the bight or bridge portion 6. The bristles of the brush unit 9 are secured in the twist of the leg members in the usual and well known manner. The brush units extend from substantially the tops of the leg members 7 to the ends of the terminals of the lower bent portions 8.

The wires forming the frame or brush core 5 at the bight or bridge 6 have adjacent portions bent outwardly from one another to provide therebetween suitable guide means for an operating bar 10 that extends centrally and longitudinally of the frame as suggested in Figures 1 and 2.

Longitudinally spaced pairs of oppositely disposed arms 11 are pivoted at their respective inner ends to the bar 10 as at 12, and U-shaped members 13 are pivotally secured to the outer ends of the arm as at 14 and fixedly embrace adjacent portions of the side or leg members 7.

For the upper end of the actuating bar 10 there is provided a suitable handle 15.

The resiliency of the wire frame or core 5 has a tendency to normally maintain the parts in the position shown in Figure 2, whereby the brush units 9 will be disposed closely together, and when in this position, the brush is readily inserted downwardly into a bottle B such as a milk bottle and when the end portions 8 of the legs or sides 7 engage the bottom of the bottle, a downward pressure upon the handle 15 will cause the actuating bar 10 to move downwardly relative to the frame 5 causing the arms 11 to be forced outwardly, and as a result, the legs or sides 7 of the brush will be brought into engagement with the inner wall of the bottle and at the same time, the bottom of the brush will be extended to entirely engage with the inner face of the bottle bottom as shown in Figure 1.

It will be also noted that during the expansion of the frame or core 5, the upper portion of the latter is drawn into the bottle by the flexing of the upper portion of the leg or side members 7 against the sides of the bottle to conform to the shape of the inclined inner surfaces of the sloping shoulders of the bottle. (See Figure 1).

By holding the handle 15 in its lowered position, and by turning the same, with the parts in the position shown in Figure 1, it will be apparent that the interior of the bottle along the sides and at the bottom thereof can be thoroughly cleansed in a very short period of time.

By pulling upwardly on the handle 15, the sides or legs 7 will be moved to the position shown in Figure 2 and the frame or core 5 will assume its original shape whereupon it may be withdrawn through the neck of the bottle.

Even though I have herein shown and described the preferred embodiment of the invention, it is to be understood that the same is susceptible of changes, modifications and improvements coming within the scope of the appended claim.

Having thus described my invention, what I claim as new is:

A bottle cleaning brush comprising an inverted substantially U-shaped frame formed of spring wire and consisting of a pair of spaced oppositely disposed L-shaped leg members connected at their upper ends by a bridge portion and having a respective lower bent portion disposed inwardly of the frame and laterally of each other, an operating bar 30 extending centrally and longitudinally of the frame with its upper end disposed slidably through the bridge portion of the frame, longitudinally spaced pairs of oppositely disposed arms pivoted at their respective inner ends to said bar for relatively opening and closing movement inwardly of the frame, U-shaped members pivotally secured to the outer ends of said arms and fixedly embracing adjacent portions of said leg members, said frame being tensioned to normally hold the leg members close together, and the said arms in relatively closed relation, said bar being shiftable relative to the frame for opening the said arms and separating the said leg members.

In testimony whereof I affix my signature.

PAUL T. EDGAR.
